CLAIM

The ornamental design for golfer's utility chest, as shown and described.

DESCRIPTION

FIG. 1 is a perspective view of a golfer's utility chest;
FIG. 2 is a front elevational view thereof;
FIG. 3 is a right side elevational view thereof, with the opposite side being a mirror image thereof;
FIG. 4 is a top plan view thereof;
FIG. 5 is a bottom plan view thereof;
FIG. 6 is a rear elevational view thereof; and,
FIG. 7 is a perspective view showing, in particular, the present invention's segmented, top cavity and the golf ball receiving holes formed through one of the drawers.
The broken line showing of golf balls and golf tees is for illustrative purposes only and forms no part of the claimed design.
